CLAIM

(21) Appl. No.: **29/542,789**

The ornamental design for the oral rinse suction evacuation dental appliance, as shown and described.

(22) Filed: **Oct. 16, 2015**

DESCRIPTION

(51) LOC (10) Cl. **24-02**

FIG. 1 is a right side perspective view of an oral rinse suction evacuation dental appliance according to the present invention, showing a disposable sanitary disk component attached to a body component thereof;

(52) U.S. Cl.

FIG. 2 is a reduced perspective view thereof, showing the oral rinse suction evacuation dental appliance in use;

USPC **D24/152**; D24/112; D24/176

FIG. 3 is an exploded right side elevation view, showing the disposable component removed from the body thereof;

(58) **Field of Classification Search**

FIG. 4 is a left side elevation view thereof;

USPC D24/152, 108, 112–113, 176–177

FIG. 5 is a top plan view thereof;

CPC A61C 17/043; A61C 17/0202; A61C

17/0208; A61C 17/00; A61C

17/005; A61C 17/04; A61C 1/16

FIG. 6 is a bottom plan view thereof;

See application file for complete search history.

FIG. 7 is an exploded front oblique view thereof, showing the disposable component removed from the body thereof;

(56) **References Cited**

FIG. 8 is an exploded rear oblique view thereof, showing the disposable component removed from the body thereof;

U.S. PATENT DOCUMENTS

FIG. 9 is an exploded front end perspective view thereof, showing the disposable component removed from the body thereof; and,
